UNITED STATES PATENT OFFICE.

EMORY M. THOMAS, OF BUCKNER, MISSOURI.

GASOLINE GUN.

Application filed October 21, 1922. Serial No. 596,004.

To all whom it may concern:

Be it known that I, EMORY M. THOMAS, citizen of the United States, residing at Buckner, in the county of Jackson and State 5 of Missouri, have invented certain new and useful Improvements in Gasoline Guns, of which the following is a specification.

The present invention is a gasoline gun and has for the primary object thereof, the 10 production of a device adapted to be carried in the pocket, and having means for discharging a combustible fluid therefrom such as gasoline or the like, this combustible fluid adapted to be ignited in a manner 15 hereinafter described whereby a sheet of flame may be directed towards a burglar or highway man in case the owner or user of the device is assaulted or held up.

A further object of this invention resides 20 in the provision of an article of the above nature that is simple of construction, compact in form, inexpensive of manufacture and efficient in operation.

The nature and advantages of the invention will be better understood when the 25 following detailed description is read in connection with the accompanying drawings, the invention residing in the construction, combination, and arrangement of parts as 30 claimed.

In the drawings forming part of this application, like numerals of reference indicate similar parts in the several views, and wherein:—

35 Figure 1—is a side elevational view of a gun constructed in accordance with the present invention.

Figure 2—is a longitudinal cross sectional view of the device shown in Figure 1, a 40 portion of the same being set forth in elevation.

Figure 3—is an enlarged detail cross sectional view of a portion of the gun, the same being fragmentarily shown, and

45 Figure 4—is a transverse sectional view upon the line 4—4 of Figure 1, looking in the direction of the arrows.

With particular reference to the several views, there is shown a longitudinally extending fluid barrel or cylinder 1 closed at its front end 2, and open at its rear end 3, a portion of the barrel at the rear end being screw threaded as shown for screw threadedly receiving a cap 4. The upper surface of 50 the barrel or cylinder 1 is provided with

spaced sights 5 resembling the sights generally found on revolvers and guns.

Formed as an integral portion of the barrel or cylinder 1 is a longitudinally extending rib portion 6 upon the bottom wall 80 thereof, this rib portion being so formed as to provide a handle 7 and trigger guard 8. Positioned for sliding movement within the said cylinder is a piston 8 carried by the usual piston rod 9. Surrounding the said rod 9, and between the adjacent walls of the piston 8 and cylinder cap 4 is a relatively strong helical spring 10 for normally tending to force the said piston forwardly within the cylinder. The rod 9 extends through a central opening in the cap 4, and has rigid connection with a reciprocating rectangular rod member 11 hereinafter more fully described. The connection between the piston rod 9 and the 75 rod 11 is in the form of a rectangular plate 12 having a pair of finger openings 13 therein for the reception of the fingers of the user of the gun for retracting both the piston rod 9, and the other rod 11. 80

As more clearly shown in Figures 2 and 4, the rod 11 is slidably received within a longitudinally extending groove 14 of the depending portion 6 formed upon the barrel or cylinder 1. The upper surface of the 85 sliding rod 11 is channeled as at 15 for a portion of its length, and formed within the forward portion of this channel are rack teeth 16, which rack teeth engage similar teeth upon a gear wheel 17 mounted for 90 rotary movement within the outer end of the depending portion being suitably channeled as shown in Figures 2 and 3 for receiving this gear wheel therein. Also positioned for rotary movement within this 95 channeled portion of the depending web 6 is another relative smaller gear wheel 18 having continuous mesh with the said gear 17. Formed as an integral part of the last mentioned wheel 18 and adapted to rotate 100 therewith is another wheel 19 having its outer periphery suitably roughened as shown in Figure 3, which roughened wheel is adapted for frictional contact with a piece of flint or other spark producing material, 105 conveniently received within a hollow nipple 21 formed upon the lower adjacent end of the closed end wall 2 of the cylinder 1.

Centrally formed within the closed end 110

2 of the cylinder 1 is an outlet 22 surrounded at its outer edge by a hollow screw threaded nipple 23 for receiving therein a disk of waxed paper or the like 24 to be there retained by a screw threaded cap 25 for effectively sealing a combustible fluid within the cylinder 1.

A portion of the underside of the sliding rod or bar 11 is toothed as at 26 forming 10 a plurality of teeth thereon for engagement with one end of a spring actuated dog member 27 carried by the depending web 6 of the barrel 1, for retaining the piston 8 retracted within the cylinder 1 when the same 15 is rearwardly moved within the cylinder. For releasing the said dog 27 from the rack portion 26 of the rod 11, for consequently allowing the piston 8 to move forwardly within the cylinder, pressed forward by the 20 helical spring 10, a pivoted spring pressed trigger 28 is provided, the free portion of the same having engagement with a portion of the dog 27 when a pull is exerted upon the said trigger.

25 In view of the above description, it will be readily understood that the piston member 8 is primarily drawn backwards within the cylinder for imparting a similar rearward movement to the rod 11 at which 30 time, the said cylinder may be filled with gasoline or other combustible fluid, through the nipple 23 upon the end wall 2 thereof. Through the racked surface 26 of the rod 11 engaging the pivoted dog 27, this piston 35 will be maintained in a retracted position, at which time, the sealing disk 24 may be secured to the nipple 23 for effectively sealing the liquid within the cylinder. Should 40 occasion ever arise to use the gun, all that is necessary is to exert a pull upon the trigger 28, which will release the dog 27 from the rod 11 allowing the piston to move forwardly within the cylinder in view of the coiled spring 10, which action breaks 45 the sealing disk for allowing the liquid to escape, at which time, it is ignited by sparks occasioned from the rotation of the gear

wheels 17 and 18 and also the roughened wheel 19 frictionally engaging the piece of flint or the like 20, this action creating 50 sparks at the outlet end of the cylinder.

While it is believed that from the foregoing description, the nature and advantages of the invention will be readily apparent, I desire to have it understood that 55 I do not limit myself to what is herein shown and described, and that such changes may be resorted to when desired as fall within the scope of what is claimed.

What I claim as new is:—

1. In a device of the class described, a combustible fluid chamber, a spring pressed plunger therein adapted for expelling the fluid from the chamber, and means operable by the action of the plunger for igniting the fluid as it is expelled from the cylinder. 65

2. In a device of the class described, a combustible fluid cylinder, a spring pressed plunger within the cylinder for expelling 70 the fluid therefrom, means positioned upon the outlet end of the cylinder for sealing the liquid therein, when the plunger is in a retracted position, said means adapted to be disrupted by a forward movement of 75 the piston within the cylinder, and means for igniting the fluid as the same is discharged therefrom.

3. In a device of the class described, a combustible fluid chamber, a spring pressed 80 plunger within the chamber adapted for discharging the liquid therefrom when the same moves forwardly therein, a sliding rod member externally of said cylinder, the movement of which is controlled by the 85 movement of said piston, and means at the outlet end of said cylinder for igniting the fluid as it is discharged therefrom, said means being operable by the movement of 90 said sliding rod.

In testimony whereof I affix my signature.

EMORY M. THOMAS.
